(57) **CLAIM**

The ornamental design for a crutch bag, as shown and described.

DESCRIPTION

FIG. 1 is perspective view of the crutch bag my new design, showing open flaps.

FIG. 2 is a front elevational view thereof.

FIG. 3 is a back elevational view thereof.

FIG. 4 is an elevational view of one side of the device of my new design.

An elevational view of the side opposite to that shown in FIG. 4, is a mirror image thereof.

FIG. 5 is a top plan view thereof; and,

FIG. 6 is a bottom plan view thereof.

1 Claim, 4 Drawing Sheets

Fig. 2

Finger.
